UNITED STATES PATENT OFFICE.

ALBERT O. BUCKIUS, JR., OF CHICAGO, ILLINOIS, ASSIGNOR TO THE
MALLEABLE CASTINGS COMPANY, OF CLEVELAND, OHIO, A COR-
PORATION OF OHIO.

JOURNAL BOX AND LID.

No. 851,063.

Specification of Letters Patent.

Patented April 23, 1907.

Application filed August 31, 1905. Renewed September 17, 1906. Serial No. 334,980.

To all whom it may concern:

Be it known that I, ALBERT O. BUCKIUS, Jr., of Chicago, Cook county, Illinois, have invented a new and useful Journal Box and Lid, of which the following is a full, clear, and exact description, reference being had to the accompanying drawings, forming part of this specification, in which—

Figure 1 shows a partial longitudinal section on the line I—I of Fig. 2, showing the lid in closed position; Fig. 2 is a vertical cross-section on the line II—II of Fig. 1; and Fig. 3 is a view similar to Fig. 1 showing the lid in open position.

It is desirable that journal boxes for railway cars should have tightly fitting and dust-proof lids and that the lids should be firmly held to the seat or face of the box at all times; that the mechanism should be simple and compact, and not subject to be disordered by the severe usage to which the parts of railway cars are subjected. In these respects my present invention is an improvement upon all prior devices known to me.

In the drawings, 2 represents the axle box, and 3 the lid which may be of usual external form, hinged to the lug 4 of the box by a pivot pin 5. The closing mechanism which is the subject of my present invention comprises a spring 6, preferably a coiled spring, which bears at one end on a seat or socket 7 on the inside of the lid and at its other end bears against a bell crank lever 8 pivoted to the inner side of the lid between lugs 9. The upper arm of the lever bears against a projecting part 10 of the lug of the box which is preferably so shaped that when the lid is open the end of the lever bears against the outer face of the lug, and that as the lid is closed the end of the lever will pass back of the lug into a rear recess 11.

As the lid is opened from its closed position its bearing against the downwardly projecting portion of the lug will turn the lever on its fulcrum and will compress the spring, but when the lid is fully opened, the spring though compressed will not exert a closing tendency upon the lid because of the passing of the lever to the front side of the lug which will cause the lever to tend to hold the lid open. In closing the lid, as soon as the lever arm passes the middle of the projecting portion of the lug, the reaction of the spring will press the lid firmly towards the box and will hold it against the same with a constant pres-

sure, for even when the lid is closed the spring is not entirely relaxed. The inner face of the lid may be formed with a rib 12 at its lower end which fits within the lower edge of the box opening; also with an upper rib 13 which bears against the upper edge of the box opening when the lid is closed.

The device is very simple, strong and durable.

Within the scope of my invention as defined in the claims the parts may be modified in many ways, since

What I claim is:—

1. A journal box having a hinged or pivoted lid, a lever pivoted to the inner side of said lid, and a spring seated between a bearing on the lid and one arm of the lever, the box having an internal cam-bearing with which the other arm of said lever contacts to hold the lid in both open and closed position; substantially as described.

2. A journal box having a hinged or pivoted lid, a bell-crank lever pivoted to the inner side of the lid, a spring bearing on the lid extending inwardly below one arm of the lever, a spring seated between said arm and bearing, there being a cam surface on the box engaged by the other arm of the lever; substantially as described.

3. A journal box having a hinged or pivoted cover provided with an inwardly projecting rib or flange which is arranged to fit against the upper edge of the box opening, a lever pivoted to the inner side of the lid, there being a cam bearing on the box for one arm of the lever, and a spring seated between the other arm of the lever and a bearing on the lid with its axis substantially parallel with the lower portion of the lid; substantially as described.

4. A journal box having a pivoted lid, a lever fulcrumed to the inner side of said lid, and a spring seated between one arm of the lever and a bearing on the lid, the box having within the lid a bearing for the other arm of said lever formed by two oppositely beveled cam surfaces which act upon the lever and spring to hold the lid in both open and closed position; substantially as described.

In testimony whereof I have hereunto set my hand.

ALBERT O. BUCKIUS, JR.
